UNITED STATES PATENT OFFICE

ALMER McDUFFIE McCAFFEE AND BONNER H. BARNES, OF PORT ARTHUR, TEXAS, AS
SIGNORS TO GULF REFINING COMPANY, OF PITTSBURGH, PENNSYLVANIA, A COR-
PORATION OF TEXAS

PETROLEUM DISTILLATION

Application filed September 17, 1926. Serial No. 136,100.

This invention relates to petroleum distillation; and it comprises a method of obviating the ill effects of acid petroleum vapors on still walls in operations involving displacement of such vapors by steam blown into the still above the oil level wherein the incoming steam carries a modicum of alkaline material, usually occurring as a spray of caustic soda solution; all as more fully hereinafter set forth and as claimed.

In various relations in the art of petroleum distillation it is necessary to introduce steam into the vapor space of a still at a time when the walls of the still and the vapors in the still may carry acid matters causing corrosion with the aid of such steam. For example, in a prior Patent 1,578,053, March 23, 1926, McAfee has described and claimed a process of removing residues from stills for converting high boiling oils into low boiling oils and operation with the use of aluminum chlorid. In the routine of the process described and claimed, one operation is displacing oil vapors in the still by steam blown in at the top. In this operation, it has now been found of great advantage to alkalinize the steam somewhat, thereby neutralizing any acid which may develop by hydrolytic action of the steam on aluminum chlorid, as well as decomposing any aluminum chlorid which may be present as such on the walls of the still. Alkalization may be effected in various ways; but the most convenient way is to spray a solution of caustic soda into the current of ingoing steam. Carbonate of soda (ordinary soda ash) may be used but it is not more advantageous; nor is it as convenient to handle. The same is true of milk of lime and a variety of other alkaline materials. Ammonia gas can be used but is ordinarily precluded by considerations of cost.

The same principle of using alkalinized steam to protect still walls is of advantage in various other relations in petroleum refining where it is necessary or desirable to displace acid vapors by steam. In many methods of handling petroleum oils it becomes necessary to distil a somewhat acid oil after a treatment with sulfuric acid and we have found it an advantage in such distilla-

tions to introduce some alkalinized steam as overhead or top steam; that is, steam introduced into the still above the oil level. Distillation is carried on in the usual way but a little alkalinized steam is blown into the still during distillation. The same principle of neutralizing any acid materials which may occur on the walls of the still applies here as in the foregoing operation, where alkalinized steam is used for blowing out vapors after an aluminum chlorid distillation.

In many cases the use of alkalinized overhead steam in this way is an advantage in petroleum distillation, even where no prior acid treatment has been used. For example, many crudes carry enough acidity to make use of a little alkalinized top steam of advantage in prolonging the life of the still and of the vapor line.

In the accompanying drawing is shown, more or less diagrammatically, an apparatus utilizing the present invention. The view is in central vertical section, certain parts being in elevation.

The figure is intended to illustrate the utilization of the present invention in such a process as that described in the acknowledged Patent 1,578,053. In this showing—

Element 1 is a still of known type for utilizing the converting action of aluminum chlorid on high boiling oils. It is provided with internal stirring mechanism 2 and is supported on the furnace walls 3. The still is provided with tar plug 4 operated by rod 5. It carries the usual manhole 6 and vapor outlet means 7 leading to condensers (not shown). Lines 8 and 9 are provided for pumping up and/or circulating the oil through outside cooling coils, not shown. At the top of the still it is provided with the usual overhead steam connection 10.

In the routine of use of this type of still in the way disclosed in the prior Patent, 1,578,053, after distillation is complete, the contents of the still are cooled by circulating cold oil through the still and outside cooling means. Oil vapors in the still are displaced by means of top steam coming in through inlet 10. Following are other operations by which the still is washed out. The present

invention relates more particularly to the use of steam through 10. As shown, line 10 is provided with gate valve 11 and injector 12. Above the injector is lock box 13 into which 5 passes caustic soda solution via needle valve 14 and pipe 15. Pipe 15 communicates with pipe 16 leading to any suitable source of any convenient alkali, such as caustic soda solution, under such pump pressure as may be desired. Steam enters the system through pipe 10 10 provided with valves 18 and 19 and having valved steam bleed 20.

As will be seen, during the blowout stage of the operation of the still, the entering 15 steam can receive an addition of any desired amount of any convenient alkali.

In using the present invention with other stills, the organization illustrated in connection with pipe 10 is ordinarily employed; 20 pipe 10, in such a case, entering the still at any point where top steam is usually introduced.

What we claim is:—

1. In the distillation of petroleum oils 25 under conditions wherein the vapors produced contain acids, the process of removing such acid vapors from the still upon cessation of the distillation, which comprises blowing alkalized steam into the vapor space of the 30 still, and allowing the vapors displaced thereby to escape from the still.

2. In the distillation of petroleum hydrocarbons by means of aluminum chlorid wherein acid vapors are formed, the process 35 of removing such acid vapors from the still at the conclusion of the distillation by introducing into the vapor space of the still sufficient alkalized steam to displace the vapors, and allowing the vapors to escape from the still.

40 3. The process of preserving metal receptacles in which vapors of acid character have been produced through the heating of petroleum oils, which comprises forcing alkalized steam into the upper part of the receptacle 45 where vapors have collected after such heating and allowing the vapors to escape and be displaced by said steam.

4. In the distillation of petroleum oils 50 under conditions wherein the vapors produced contain acids, the process of removing such acid vapors from the still upon cessation of the distillation by blowing a mixture of steam and caustic soda solution into the vapor space of the still, and allowing the 55 vapors displaced thereby to escape from the still.

5. In the distillation of petroleum hydrocarbons under conditions wherein acid vapors 60 are produced, the process of removing such acid vapors from the vapor space of the still at the conclusion of the distillation, which comprises admitting steam to the vapor space of the still, adding to the steam on its way to the still a solution of an alkali, and permitting escape of the vapors from the vapor 65

space of the still and displacement of them by the mixture of steam and alkali.

In testimony whereof, we have hereunto affixed our signatures, at Port Arthur, Texas, this 14th day of September, 1926.

ALMER McDUFFIE McAFFEE.
BONNER H. BARNES.
